CHAIR

Karl Luebke, Rheda-Westfalen, Germany, assignor to Luebke KG, Rheda-Westfalen, Germany

Filed Aug. 31, 1972, Ser. No. 285,523

Claims priority, application Germany Mar. 1, 1972

Term of patent 14 years

Int. Cl. D6—01

U.S. Cl. D6—65

FIG. 1

FIG. 3

FIG. 1 is a perspective front view of the chair showing my new design;

FIG. 2 is a perspective rear view thereof; and

FIG. 3 is a perspective side view.

The side view of the chair not shown in the drawing has an appearance identical with the appearance of the side view shown in FIG. 3 of the drawing.

I claim:

The ornamental design for a chair, substantially as shown and described.
